UNITED STATES PATENT OFFICE.

ALBERT W. WINSHIP, OF UTICA, NEW YORK, ASSIGNOR TO W. W. WINSHIP & SONS, INC., OF UTICA, NEW YORK, A CORPORATION.

CLOTHES-RETAINING RACK.

Application filed August 28, 1924. Serial No. 734,576.

To all whom it may concern:

Be it known that I, ALBERT W. WINSHIP, a citizen of the United States, and a resident of Utica, in the county of Oneida and 5 State of New York, have invented certain new and useful Improvements in Clothes-Retaining Racks; and I do hereby declare that the following is a full, clear, and exact 10 description thereof, which will enable others skilled in the art to which it appertains to make and use the same, reference being had to the accompanying drawings, and to the reference numerals marked thereon, which 15 form part of this specification.

My present invention relates to clothes retaining racks as applied more particularly to wardrobe trunks.

The purpose of my invention is to provide a clothes retaining rack of new and improved 20 construction and of such form that it may be applied to a variety of places.

A further purpose is to provide an article of the class described which is so constructed as to automatically hold itself in place upon 25 slideways where placed and yet be readily adjustable or entirely removed by a simple motion.

Another object is to provide a clothes retaining rack which is especially well adapted 30 to hold itself in place against the shocks and vibrations incident to handling a trunk.

Fig. 1 is a perspective view of a clothes retaining rack embodying my invention with sufficient of a wardrobe trunk shown to 35 illustrate the use of the rack.

Fig. 2 is a front elevation of the left hand 40 slideway 13 and its rack supporting clutch and adjacent parts of the structure.

Fig. 3 is a side view of the right hand rack 45 supporting clutch, spring and slideway as seen from the right hand side thereof, the hook of the clutch being cut away to more clearly show the co-operation of the parts.

While I have illustrated and described my 50 invention in connection with a wardrobe trunk it will be obvious that the invention is not limited to use simply with a wardrobe trunk but may be applied to trunks and sample cases where clothes are carried in a more or less extended position and indeed the invention may be applied to clothes presses or cupboards where it is desired to hold the clothes in position.

In the drawings I have illustrated my 55 invention in connection with a wardrobe trunk

having clothes hangers 8 slidably suspended from supports 9 attached to the opposite sides 10 of the wardrobe compartment, said wardrobe compartment having an open front closed by a door 11 and generally 60 having an open top closed by a top cover 12.

A little below the supports 9 there is supported from each side wall a slideway 13 preferably rectangular in vertical cross section as indicated in the drawings and rigidly supported in horizontal position a short distance from the side wall by means of a bracket 14. The part of the bracket adjacent the slideway is narrower than the height of the slideway 13 thus leaving a 70 portion of the side 15 of the slideway facing adjacent trunk side clear for the passage of the outwardly and downwardly turned point 16 of the rack clutch 17.

The clothes retaining rack consists of a 75 pair of depending side members 18 connected near their upper ends by top cross piece 19 and near their lower ends by a bottom cross piece 20.

To each upper corner of the clothes retaining rack is rigidly secured the rack supporting clutch 17. This clutch comprises a long depending shank portion 21 fitting against the outer surfaces of the side members 18 of the rack, said shank portion extending from the top of the side member 80 down a considerable distance on the rack and rigidly secured to the side member of the rack as by screws 22. At the top of the rack the strip of metal from which the 85 clutch is preferably formed is bent back sharply over the top of the side members of the rack forming a horizontal portion 23 with an upper face 24. Beyond this portion 90 the clutch has an upwardly extending portion 25 a little greater in height than the height of the slideway 13. Beyond the upright 25 the clutch again extends outwardly forming a top portion 26 extending over the top of the slideway 13 and beyond 95 this top 26 the metal is again turned down forming the part 16 already mentioned which engages the side 15 of the slideway 13 adjacent the trunk side and above the narrower portion of the bracket 14.

By reference to Figs. 1 and 2 it will be seen that each clutch 17 is securely mounted upon its slideway and particularly that the top face 24 of the portion 23 of the clutch engages substantially the entire width 100 105 110

of the bottom edge of the slideway and that the upstanding portion 25 of the clutch extends along the entire exposed side of the slideway 13 and is the side of the slideway 5 towards the clothes and that the top 26 covers the top edge of the slideway and that the downwardly extending projection 16 engages the inner surface 15 of the slideway.

10 As suggested in Fig. 1 and plainly shown in Fig. 3 the slideway engaging opening of the clutch between the top surface 24 of the portion 23 and the lower portion of the bottom 26 is a little greater 15 in height than the height of the slideway 13 and is disposed at a little less than a right angle to the general plane of the rack and slopes downwardly and toward the inner side of the rack so that the bottom edge 27 of the top 26 and the outer edge 28 of the face 24 tends to come into 20 binding contact with the top and bottom edges respectively of the slideway 13 as the rack tends to drop to vertical position. It will now be seen that as long 25 as these edges are sharply brought into this binding engagement by the rack being swung outwardly upon its clutches to vertical position the rack will be held 30 tightly in the position where placed. Under some circumstances the thickness of the bulk of the clothes pressed back of the rack will be sufficient to hold the rack in such binding position. Under many 35 circumstances, however, it is not desired to press the clothes tightly enough by the rack to give the rack the desired tension and under other circumstances a temporary jolt or violent movement of the trunk 40 will temporarily swing the bottom of the clothes rack inwardly enough to temporarily release the binding engagement of the clothes and allow the rack to be pushed or moved bodily outward upon the slide- 45 ways.

In order to overcome these difficulties I have provided in combination with the parts heretofore described a pair of springs 29 which will constantly but yieldingly hold the rack in position to have its clutches 50 firmly engage the slideways.

Each of the springs 29 has its flat lower half 30 rest directly against the bottom side of either of the rack uprights 18 and 55 permanently secured thereto as by bolts 31. The upper half of said springs extends upwardly and curves inwardly and has its upper end 32 engaging the lower edge of the slideway 13. The tension of these two springs

is sufficient to swing the rack outwardly 60 upon its clutches until the clutches sharply engage the slideways and thus the rack is securely held in place.

When it is desired to loosen the rack or draw it outward the bottom of the rack 65 is pushed inwardly overcoming the tension of the springs 29 and allowing the rack to be moved inwardly or outwardly or entirely withdrawn from the slideways.

With a clothes retaining rack embodying 70 my invention it will be seen that the clothes may be securely held in position in the wardrobe without having to press the clothes so tightly as to crease or disfigure them. The constant pressure of the springs 75 upon the rack is sufficient to hold the rack in place against jolts or shocks when the trunk is being moved.

What I claim as new and desire to secure by Letters Patent is:

1. The combination with a wardrobe trunk of a pair of horizontally arranged slideways spaced from the inner sides of the trunk, a clothes retaining rack, clutches secured to the rack and slidingly mounted 85 on said slideways, said clutches being adapted to bindingly engage the slideways when the bottom of the rack is swung outwardly relative to its top, and springs mounted on said rack tensioned to swing 90 its bottom outwardly.

2. The combination with a wardrobe trunk of a pair of horizontally arranged slideways spaced from the inner sides of the trunk, a clothes retaining rack, clutches 95 secured to the rack and slidingly mounted on said slideways, said clutches being adapted to bindingly engage the slideways when the bottom of the rack is swung outwardly relative to its top and leaf springs 100 mounted on said rack with their upper inner ends engaging said slideways and tensioned to swing its bottom outwardly.

3. The combination with a clothes compartment of a pair of horizontally arranged 105 slideways spaced from the inner sides of the compartment, a clothes retaining rack, clutches secured to the rack and slidingly mounted on said slideways, said clutches being adapted to bindingly engage the 110 slideways when the bottom of the rack is swung outwardly relative to its top and springs mounted on said rack tensioned to swing its bottom outwardly.

In witness whereof I have affixed my 115 signature, this 29th day of July 1924.

ALBERT W. WINSHIP.
